US00D608829S

(12) **United States Design Patent**
Nelson et al.

(10) **Patent No.:** **US D608,829 S**
(45) **Date of Patent:** **** Jan. 26, 2010**

(54) **MATERIAL CORNER SHAPER**

(75) Inventors: **Douglas Nelson**, Madison, WI (US); **Luc Lam**, Chicago, IL (US); **Lisa Painter**, Madison, WI (US); **Rebecca Lidstrom**, Madison, WI (US); **Peter Cooper**, Bronte (AU); **Sam Trewartha**, Crows Nest (AU)

(73) Assignee: **Fiskars Brands, Inc.**, Madison, WI (US)

(**) Term: **14 Years**

(21) Appl. No.: **29/319,508**

(22) Filed: **Jun. 10, 2008**

(51) **LOC (9) Cl.** **19-02**

(52) **U.S. Cl.** **D19/72**

(58) **Field of Classification Search** D8/50, D8/98; D18/14, 19; D19/72; 83/167, 467.1, 83/468, 468.2, 549, 588, 618, 620, 633, 651, 83/684; 101/31.1, 298

See application file for complete search history.

(57) **CLAIM**

We claim the ornamental design for a material corner shaper, as shown and described.

DESCRIPTION

FIG. 1 is a perspective view of a material corner shaper, showing our new design;

FIG. 2 is a top view of the material corner shaper in FIG. 1;

FIG. 3 is a right side view of the material corner shaper in FIG. 1;

FIG. 4 is a rear view of the material corner shaper in FIG. 1; FIG. 5 is a bottom view of the material corner shaper in FIG. 1;

FIG. 6 is a left side view of the material corner shaper in FIG. 1; and,

FIG. 7 is a front view of the material corner shaper in FIG. 1. The broken lines shown are for illustrative purposes only and form no part of the claimed design.
